OIL AND GAS WELL PACKER.

Application filed July 14, 1927. Serial No. 205,717.

This invention relates to oil or gas well packers, and it has for its object to provide a simple and efficient device of this character adapted to be lowered into a well in a contracted condition and to be thereafter expanded and brought into fluid tight engagement with the walls of the shot hole in such manner as to effectively shut off the passage of liquid or gases past the packer.

10 Further objects and advantages of the invention will be set forth in the detailed description which follows:

In the accompanying drawings,

Fig. 1 is a diagrammatic vertical sectional view, illustrating the device positioned in a shot hole, and before it has been drawn upwardly to packing position,

Fig. 2 is a view like Fig. 1, illustrating the packer drawn upwardly to pack the mouth of 20 the outlet from the shot hole,

Fig. 3 is a side elevation of the packer and associated parts,

Fig. 4 is a vertical sectional view,

Fig. 5 is an enlarged horizontal sectional view upon line 5—5 of Fig. 4, and

Fig. 6 is a side elevation of a locking collar, hereinafter described.

Like numerals designate corresponding parts in all of the figures of the drawing.

30 In the drawing 5 designates the well tubing, which includes collars 6 and 7 in its length. The lower portion of the tubing is adapted to slide through a disc 9 that is disposed within a coupling 10, and is clamped between the lower end of a metallic sleeve 11 and the upper end of a perforated anchoring sleeve 12. The lower end of an expansible rubber sleeve 13 is secured by the means of a band or wire 14 to the lower portion of the 35 sleeve 11, while the upper end of the rubber sleeve 13 is connected through the medium of a collar 15 with the tubing just below the collar 6.

The upper end of the sleeve 11 carries an 40 inwardly projecting ring 16 that is provided with diametrically opposed slots 17. The tubing carries a pair of collars 18 and 19, said collars comprising annular portions 18^a—19^a and lugs 18^b—19^b. A spring 20 bears between the underside of the collar 19, and washer 21. Washer 21, in turn, bears upon 45 a rubber packing gasket 22, which rests upon the disc 9.

With the parts in the position illustrated

in Fig. 1, the lugs 19^b of collar 19 are out 55 of line with the slot 17 of ring 16, and said ring lies between lugs 19^b, and the annular member 19^a of collar 19. Thus the parts are locked in position and there can be no endwise movement of the tubing with respect to the 60 sleeve 11, and its associated parts, and the rubber sleeve 13 is held in its longitudinally elongated condition or in laterally contracted condition, so that it may, without interference, be lowered through the well casing 22' 65 and into the shot hole 23. The lowering of the tubing and the packer is continued until the perforated anchor sleeve 12 rests upon the bottom of the shot hole.

The tubing 5 is then given a quarter turn 70 to bring the lugs 19^b into alignment with the slots 17, after which the tubing is lowered, with relation to sleeve 11 and its associated parts, until the lugs 18^b of collar 18 have passed through the slot 17. Then the tubing 75 is given another quarter turn to bring the lugs 18^b out of alignment with the slots 17 and this locks the tubing in its lowered position. The downward movement of the tubing, with respect to the sleeve 11, expands the 80 rubber sleeve to the position illustrated in Fig. 5. Then the tubing is drawn upwardly until the expansible member constituted by the rubber sleeve contacts with the wall of the shot hole adjacent the lower end of the 85 casing 22'. A further upward movement of the tubing and sleeve 11 (which is now locked to the tubing) causes a further expansion of the rubber sleeve and brings it to the position illustrated in Fig. 6, at which time it 90 completely seals the entrance to the shot hole, both with respect to the interior and exterior of the well casing 22', thereby positively preventing the escape of either liquid or gases from the shot hole. 95

When it is desired to remove the packer the operation is reversed. That is to say, the tubing, which up to this time has been held in place by suitable means at the surface of the well, is lowered, until the sleeve 12 rests 100 upon the bottom of the shot hole. Then the tubing is given a quarter turn to bring the lugs 18^b into alignment with the slots 17 so that when the tubing is lifted the spring 105 30 may act to thrust sleeve 11, and associated parts, downwardly with respect to the tubing, thereby restoring the parts to the position illustrated in Fig. 1, it being understood that

after the lugs 19^b have passed through the slots 17, the tubing will be given a quarter turn to lock collar 19 to ring 16.

The aforesaid action brings the sleeve 13 to its contracted position so that the whole structure may be withdrawn from the well.

Attention is directed to the fact that the packing washer 22 serves to prevent the entry of either fluids or gases, under pressure, to the interior of sleeve 11 and the expandable member 13.

We wish further to state that we contemplate the use of this packer in conjunction with the conventional disc trip or similar mechanism.

It is to be understood that the invention is not limited to the precise construction set forth, but that it includes within its purview any changes which fairly come within either the terms or the spirit of the appended claims.

Having described our invention, what we claim is:

1. A well packer comprising a well tubing, a tubular member encircling said tubing, an expandable sleeve, the lower end of which is secured to said tubular member, and the upper end of which is engaged with said well tubing, the parts being so arranged that the expandable sleeve is bulged outwardly to an extent to present an upwardly facing surface of contact when the well tubing is moved downwardly with respect to said tubular member and means for locking the well tubing to the tubular member to thereby hold said sleeve in its bulged position when the well tubing is drawn upwardly to bring said contact surface into packing engagement with the mouth of the outlet from a shot hole.

2. A structure as recited in claim 1, in combination with means for sealing the lower end of the tubular member against the entrance of either fluids or gases under pressure.

3. A device of the character described, comprising in combination a well tubing, a tubular member through which said well tubing passes, a rubber sleeve the lower end of which is secured to the outside of said tubular member, and the upper end of which is engaged with the well tubing, and locking members between said tubular member and the well tubing operable under turning movement of the well tubing with respect to the tubular member for locking the well tubing against movement with respect to said tubular member.

4. A structure as recited in claim 3, in combination with a spring tending to thrust the well tubing upwardly and the tubular member downwardly with respect to each other.

5. A device of the character described, comprising in combination a well tubing, a tubular member through which said well tubing passes, a rubber sleeve the lower end

of which is secured to the outside of said tubular member, and the upper end of which is engaged with the well tubing, locking members between said tubular member and the well tubing operable under turning movement of the well tubing with respect to the tubular member for locking the well tubing against movement with respect to said tubular member, said locking means being operable at both the upper and lower limits of movement of the well tubing.

6. A device of the character described, comprising in combination a well tubing, a tubular member through which said well tubing passes, a rubber sleeve the lower end of which is secured to the outside of said tubular member, and the upper end of which is engaged with the well tubing, and locking members between said tubular member and the well tubing operable under turning movement of the well tubing with respect to the tubular member for locking the well tubing against movement with respect to said tubular member, a gasket at the lower end of said tubular member, and a spring acting between said gasket and an element of said locking mechanism.

7. A device of the character described, comprising a well tubing, a tubular member surrounding the same, a rubber sleeve the lower end of which is engaged with said tubular member and the upper end of which is engaged with the well tubing, a slotted ring carried by the upper end of the tubular member, a pair of spaced locking collars upon the well tubing comprising lugs adapted to be passed through the slots of said ring and to be locked against movement with respect to said ring by having their lugs turned out of registry with said slots, and a spring disposed within the tubular member tending to thrust said tubular member downwardly with respect to the well tubing.

8. A structure as recited in claim 7, in combination with packing means for sealing the lower end of the tubular member and upon which said packing means the lower end of said spring acts.

9. A well packer comprising a well tubing, a tubular member encircling said tubing, an expandable sleeve, the lower end of which is secured to said tubular member, and the upper end of which is engaged with said well tubing, the parts being so arranged that the expandable sleeve is bulged outwardly to an extent to present an upwardly facing surface of contact when the well tubing is moved downwardly with respect to said tubular member, means for locking the well tubing to the tubular member to thereby hold said sleeve in its bulged position when the well tubing is drawn upwardly to bring said contact surface into packing engagement with the mouth of the outlet from a shot hole, and packing means carried by the tubular mem-

ber through which the well tubing slides, said packing member serving to prevent the entrance of either fluids or gases under pressure to the interior of the expansible sleeve.

- 5 10. A well packer comprising a well tubing, a tubular member encircling said tubing, an expansible sleeve, the lower end of which is secured to said tubular member, and the upper end of which is engaged with said well
10 tubing, the parts being so arranged that the expansible sleeve is bulged outwardly to an extent to present an upwardly facing surface of contact when the well tubing is moved downwardly with respect to said tubular
15 member, inter-engaging locking elements between the well tubing and tubular member for locking these parts together at either their upper or lower limits of movement, the locking of the parts together, at their upper
20 limits of movement, serving to hold the said
- sleeve in elongated and laterally contracted condition, and the locking of said parts together at the lower limit of movement serving to hold the sleeve in its outwardly bulged position so that when the well tubing is 25 drawn upwardly the upwardly facing surface of contact of the sleeve will be drawn into packing relation to the mouth of the shot hole.
11. A structure as recited in claim 10, in 30 combination with a spring encircling the well tubing and acting to thrust the tubular member upwardly and the well tubing downwardly with respect to each other.

In testimony whereof we affix our signatures. 35
